Primary Examiner — Garth Rademaker*Assistant Examiner* — Llorellys Martinez-Rivera(74) *Attorney, Agent, or Firm* — Chainey P. Singleton; Chalker Flores, LLP(57) **CLAIM**

The ornamental design for a solar system lamp shade, as shown and described.

DESCRIPTION

FIG. 1 is a perspective view of a solar system lamp shade showing my new design;

FIG. 2 is a side elevation view thereof;

FIG. 3 is a another side elevation view thereof;

FIG. 4 is a another side elevation view thereof;

FIG. 5 is a another side elevation view thereof;

FIG. 6 is a top view thereof;

FIG. 7 is a bottom view thereof; and,

FIG. 8 is another perspective view thereof.

The broken line portions of FIGS. 1, 6 and 7 are included to show portions of the solar system shade which form no part of the claimed design.
